UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

REGENERATIVE CHANNEL OVEN.

Application filed July 6, 1921, Serial No. 482 806, and in Germany September 13, 1918. Renewed June 25, 1927.

(GRANTED UNDER THE PROVISIONS OF THE ACT OF MARCH 3, 1921, 41 STAT. L., 1313.)

The invention relates to an oven plant operated after the fashion of the channel ovens, in which the material to be heated enters in constant sequence at one end of the heating room or chamber to leave the same again at the other end when it has been brought to the requisite temperature, as is customary in connection with the burning of fireproof bricks, or in the preheating of iron or steel blocks or billets. In the present case the heating of such an oven is to be rendered possible with heat-recovery by regenerators in such a way that the material to be heated at any time comes into contact, prior to its departure from the oven, with just exactly the hottest flame in order to thus bring about a complete utilization of the heat developed. For that purpose the oven plant is embodied in the shape of two parallel chambers or tunnels separated in the burning zone by a central partition, which chambers are charged uniformly with the material to be heated and which are so connected with a regenerative system that the fuel, gas and air, enters the heating chamber proper from the heat storage system at the end which is the outlet for the substances to be warmed up, and flows in a countercurrent to their direction of movement as they enter and pass through the burning zone; the burning fuel thence passing around the front end of the central partition of the two parallel chambers, and into the second chamber and going thence into the waste heat regenerators. With the draft reversal the direction in which the gases flow through the two heating chambers is then also reversed. Thereby the maximum heat is developed at the outlet end for the substances to be heated. In the second parallel chamber the escaping gases are reduced in temperature and are no longer hot enough to undergo the fall of temperature necessary for yielding heat but, at the same time, are not cooled sufficiently to bring about a cooling of the substances heated during the preceding operating stage.

In order to make the invention more clearly understood there is shown in the accompanying drawing means for carrying the same into practical effect, without limiting the improvements in their useful applications, to the particular embodiment thereof

which is shown for the purpose of explanation. In said drawings—

Fig. 1 is a vertical longitudinal section of a channel oven embodying the invention.

Fig. 2 is a cross section of the same on the line A—B of Figure 1.

Fig. 3 is a plan view.

Referring to the drawing, the heating chamber proper consists of two parallel chambers *a* which are separated by a central vertical longitudinal partition *b* into which chambers the substances to be warmed up, for instance, billets to be heated, enter at *c* to again leave the rear end of the heating chamber *a* at *d*. Above the heating chambers *a* the regenerators *e* and *f* are arranged, which are connected in series by the channel *g* and communicate with the heating chamber *a* through the channel *h*; for each heating chamber, two such regenerator pairs (front and rear) are provided, each pair consisting of separate parallel chambers which serve for pre-heating gas and air respectively (Fig. 2). The heating gas is fed to the respective regenerators through the conduit *i* and connections *k*, while the air enters through conduit *l* and connections *m*. All connections *k* and *m* are connected to the conduit *o* leading to the chimney, by means of valves *n*.

At one operating stage, for instance, through the regenerators shown on the left in illustration 2, gas and air will enter and warm up properly in the hot checker-work of the regenerators *e* and *f* and then enter the chamber *a* located at the left, through the left hand channels *h* and burn up here. The flame developing passes over the billets which lie on the hearth, turns about at *c* around the central partition *b* and flows rearward through the second heating chamber *a* (at the right) into the regenerators *e* and *f* (at the right) now connected to the chimney conduit *o*, which regenerators thereby absorb the surplus waste heat. After a certain period (about half an hour) all the connections are changed so that gas and air now enter on the other (right) side and flow through the plant in the opposite direction, rearward through the right hand regenerators, forward through the right hand oven channel, rearward through the left hand

oven channel and forward through the left hand regenerators to the chimney. In this connection it can be seen that the maximum temperature is always developed at the outlet end of the oven for the substances to be heated, while a certain countercurrent of gases is obtained with reference to the travel of the material.

Of importance is the fact that here the regenerators are arranged above the heating chamber, whereby an interference as regards inlet and outlet for the material is avoided and a great simplification is also brought about structurally. Of special significance is the feature that the checker work of the regenerators *e* and *f* is traversed by the gases to be heated upward from below, but downward from above by the waste heat to be cooled, because, as is well known, in this manner the best admission to regenerators is obtained and the fire-proof stone filling or checker work is heated uniformly and cooled in just the same uniform manner. Since with a regenerator extending in one piece throughout the length of the heating chamber *a* and thus possessing considerable length in comparison with its height, diagonal currents might develop, the regenerators are divided into the two compartments *e* and *f* arranged in series in the characterized manner, whereby diagonal currents are prevented.

The described construction also affords opportunity for an evolution of an operating manner described in German Letters Patent 196,532 of the applicant, inasmuch as there is connected to the inlet end of heating chambers *a* a preheating chamber *p* which can be constructed without a central partition and into which the cold substances to be pre-heated are introduced through the door *q*. Now by providing, at the front end of the chamber *p*, special flues *r* which are also connected to a chimney, it is possible, by a proper regulation of the latter, to branch off, and pass away over the substances to be pre-heated, a part of the flame or hot gases which would otherwise turn about at *e*, by means of which a natural preheating, again proceeding on the countercurrent principle, is obtained, without the efficiency of the heating proper being in any way impaired thereby. Even if this additional improvement is not a necessity, it is available wherever there exists the need of such preheating.

What is claimed is—

1. A channel oven embodying a regenerative heating system and a plurality of heating channels arranged parallel to each other, said channels being divided by a partition, said oven being arranged so that the pre-heated fuels enter one of the channels at the outlet end of said channel and flow countercurrent to the direction of movement of the materials being heated in said channel, said

burning fuel flowing around said partition and into the other burning channel in the direction of movement of the material being heated therein, and from the outlet end of said other burning channel out through the 70 outflowing regenerators.

2. An oven according to claim 1, characterized by the regenerators for gas and air being arranged in the longitudinal direction of and 75 above the oven channels.

3. An oven according to claim 1 and in which regenerators for gas and air are arranged in the longitudinal direction of and above the oven channels, characterized by the individual regenerators being partitioned into two compartments *e* and *f* communicating by means of a central channel *g* in said partition, said central channel communicably connecting the upper part of one of said compartments with the lower part of the other compartment so that they are traversed consecutively by the combustion substances to be preheated from below upward, and by the waste heat downward from above. 80 85

4. An oven according to claim 1 and in which regenerators for gas and air are arranged in the longitudinal directions of and above the oven channels and in which the individual regenerators are partitioned into two compartments *e* and *f* communicating by means of a central channel *g* in the partitions, said central channel communicably connecting the upper part of one of said compartments with the lower part of the other compartment so that they are traversed consecutively by the combustion substances to be preheated from below upward, and by the waste heat downward from above, and characterized by a part of the hot gases being removed at the turning point of the flame around the central partition *b*, and a part withdrawn by means of a pre-heating chamber *p* directly adjoining the oven. 90 95 100

5. A channel oven comprising, in combination, combustion and heating chambers side by side having a dividing longitudinal partition, regenerators above said chambers having fuel-feeding, connecting and gas-delivering means whereby the progress of the fuel while being heated is from lower to higher points in said regenerators and thence to the rear part of a combustion chamber, and the progress of the waste gases in said regenerators while heating the same is from above downward and thence to the stack, and means for controlling and reversing the direction of said fuel and waste gases. 110 115 120

6. A channel oven comprising, in combination, combustion and heating chambers side by side having a dividing longitudinal partition, and regenerators arranged above said combustion and heating chambers and having fuel delivering flues entering into the rear part of said combustion chambers at which end the articles to be heated have their exit. 125 130

7. A channel oven comprising, in combination, combustion and heating chambers side by side having a dividing longitudinal partition, regenerators above said chambers having fuel-delivering, connecting and gas-delivering means whereby the progress of the fuel while being heated is from lower to higher points in said regenerators and thence to the rear part of a combustion chamber, and the progress of the waste gases in said regenerators while heating the same is from above downward and thence to the stack, means for controlling and reversing the direction of said fuel and waste gases, and a front pre-heating chamber through which pass the articles to be heated, chimney flues at the front end of said pre-heating chamber, and chimney flues leading from the front portions of said regenerators, whereby a portion of the products of combustion passes through said regenerators and another portion thereof passes through said preheating chamber in a direction opposite to the advance of the articles to be heated.
- 15 8. A channel oven comprising, in combination, combustion and heating chambers side by side having a dividing longitudinal partition, regenerators arranged above said combustion and heating chambers and having fuel delivering flues entering into the rear part of said combustion chambers at which end the articles to be heated have their exit,
- means for reversing the direction of flow through said regenerators and heating chambers whereby the gases may be caused to circulate around said partition in either direction, a front preheating chamber through which pass the articles to be heated, chimney flues at the front end of said preheating chamber, and chimney flues leading from the front portions of said regenerators, whereby a portion of the products of combustion passes through said regenerators and another portion thereof passes through said preheating chamber in a direction opposite to the advance of the articles to be heated.
- 25 9. A channel oven embodying a regenerative system of heating comprising in combination two burning chambers arranged parallel to each other, said oven having the regenerators arranged immediately over said burning chambers and communicably connected with said burning chambers so that the material being heated is subjected to the greatest heat at the point in said channels where said material leaves said channels.
- 30 10. An oven according to claim 1, characterized by a part of the hot gases being removed at the turning point of the flame around the central partition *b* and withdrawn by means of a preheating chamber *p* directly adjoining the oven.

HEINRICH KOPPERS.
